(57) **CLAIM**

The ornamental design for a kiosk display apparatus, as shown and described.

DESCRIPTION

FIG. 1 is a partial front perspective view of a design for a kiosk display apparatus;

FIG. 2 is a partial rear view thereof;

FIG. 3 is a front view thereof;

FIG. 4 is a rear view thereof;

FIG. 5 is a left-side view thereof;

FIG. 6 is a right-side view thereof;

FIG. 7 is a top view thereof; and,

FIG. 8 is a bottom view thereof.

Any broken lines showing portions of the design are for illustrative purposes only and form no part of the claimed design.
